UNITED STATES PATENT OFFICE.

DAVID JACKSON, OF PAWTUCKET, RHODE ISLAND.

SPINDLE FOR SPINNING-MACHINES.

SPECIFICATION forming part of Letters Patent No. 399,046, dated March 5, 1889.

Application filed April 2, 1888. Serial No. 269,373. (No model.)

To all whom it may concern:

Be it known that I, DAVID JACKSON, of Pawtucket, in the State of Rhode Island, have invented a new and useful Improvement in 5 Spindles for Spinning-Machines, of which the following is a specification.

My invention has been devised with particular reference to the needs of the revolving spindle used in spinning machinery, such as 10 roving-machines, in which the spindle and its bolster have a lengthwise movement or traverse relatively to each other. To this end I form in the spindle within the limits of the portion which traverses the bolster two or 15 more annular grooves having no connection with one another, each of which grooves is filled with packing material that will absorb a suitable lubricant. The lubricant is held and retained in the packing in the grooves 20 and is only given out therefrom under the capillary attraction, as it in some sort may be considered, resulting from the rapid revolution of the spindle in its closely-fitting bolster, the oil being drawn out from the packing in 25 such quantities only as to afford the needed lubrication and being again taken up and reabsorbed in great measure by the packing when the spindle ceases to move. The packed grooves also being placed upon the spindle 30 within the limits of its traverse in the bolster, prevents the undue spreading of the lubricant upon the spindle and the damage to the bobbin which would result therefrom.

The nature of my improvement and the 35 manner in which the same is or may be carried into effect will be readily understood by reference to the accompanying drawings, in which—

Figure 1 is a sectional elevation of a roving-machine spindle and some of its appurtenances, the spindle being in elevation and the bolster and bobbin and its yarn-load being in vertical section. Fig. 2 is a view of 40 the spindle detached.

It is not necessary to identify the parts further than to say that A is the spindle, and B 45 is the bolster therefor, and C is the bobbin with its yarn-load D.

All of the parts are of the construction 50 usually found in roving-machines, except so far as concerns the construction and arrangement of the lubricating device.

In that part of the spindle which runs in the bolster I form a suitable number of peripheral annular grooves, a—three in the present instance. These grooves are packed with 55 yarn or other fibrous material, b, which will absorb and retain the lubricant. I have shown but two of the grooves packed. The bottom one of the three is left unpacked in order to 60 disclose more clearly the form of the groove.

The lubricant is absorbed and retained by this packing; is given out, as hereinbefore explained, only when the spindle is in movement, and even then only in quantity sufficient 65 for lubricating purposes.

In practice it heretofore has been necessary to chamber the bolster within which the spindle rotates in order to reduce friction as far as possible; but in so doing the bolster necessarily is weakened to such an extent that it frequently breaks during the operation of removing the bobbin. The same defect is noticeable if the bolster instead of the spindle be chambered, recessed, or grooved to receive 75 a lubricant. Such a construction, however, is not necessary when my invention is used. The bolster can, as shown, be made with a straight bore having a continuous and unbroken interior surface from end to end, which 80 adds greatly to its strength and allows the spindle to be run at a much greater rate of speed, thus enhancing the producing capacity 85 of the machine. Again, it is necessary with the spindle and bolster in common use to-day to oil the spindle twice and sometimes thrice a day. It frequently happens also that in removing the spindles from their bolsters they 90 must be driven out by a hammer, owing to neglect or failure to oil the spindles, which causes what is known as the "cutting" or roughing up of the spindle, and the consequent sticking of the latter in its bolster. By 95 my improvement this frequent oiling is not necessary. I have successfully run my improved spindles for a month's time with one oiling.

It is often the case in cotton-mills that the roving while still on the bobbins is packed away for a time until it is required for use, 100 and in such case it not infrequently happens that the roving becomes stained and unfitted for use by the oil which soaks into it from the bobbins. This result is due to oil from

the spindles getting on the bobbins in consequence of the large quantity of oil used in the ordinary methods of lubrication. By my invention, however, this trouble about the bobbins is obviated. Only so much oil is applied in the first instance as can be taken up by and contained in the fibrous packing, and then it is only furnished therefrom to the spindle as it is actually needed, and there is none 10 that comes in contact with the bobbin.

Having described my improvement, I state in conclusion that I am aware that grooves of varied form, shape, and direction for the guidance and retention of oil or other lubricant 15 have heretofore been formed in roller-journals or in the bearings thereof, and this I do not claim; but

What I do claim, and desire to secure by Letters Patent, is—

The combination, with the bolster of a roving-machine, of a spindle therefor provided with annular packed grooves for absorbing and holding the lubricant, said grooves having no communication with each other and being formed within the limits of that portion of the spindle which traverses the bolster, as and for the purposes hereinbefore set forth.

In testimony whereof I have hereunto set my hand this 28th day of March, A. D. 1888. 25 30

DAVID JACKSON.
